UNITED STATES PATENT OFFICE

2,668,389

MAGNETIC TOY

Robert W. Morrison, Kansas City, Mo.

Application March 7, 1949, Serial No. 80,040

9 Claims. (Cl. 46—45)

1

This invention relates to new and useful improvements in magnetic toys, and has particular reference to magnetic toys of the type wherein miniature vehicles or other wheeled objects are magnetically propelled.

The principal object of the present invention is the provision, in a magnetic toy wherein a miniature vehicle or the like disposed on a platform and having a magnet mounted therein adapted to cooperate with a driving magnet disposed movably beneath said platform, of a novel means whereby said miniature automobile is made to respond rapidly and accurately to movements of said driving magnet. This means includes disposition of the automobile magnet between the front and rear wheels, whereby all of the wheels are urged firmly against the platform, castering the front wheels to the rear of an upright axis whereby said front wheels will trail properly, and inclining the castering axis of said front wheels forwardly.

Another object is the provision of a magnetic toy of the class described wherein a plurality of miniature vehicles disposed on a platform are propelled respectively by individual driving magnets disposed beneath said platform, said driving magnets being so related and moved that the automobiles simulate a race, first one car then another taking the lead, the outcome of the race being a matter of chance.

Other objects are simplicity and economy of construction, dependability and ruggedness, realism of appearance, and adaptability for use in a wide variety of applications.

With these objects in view, as well as other objects which will appear in the course of the specification, reference will be had to the drawing, wherein:

Figure 1 is a plan view of a magnetic toy embodying the present invention.

Fig. 2 is a sectional view taken on line II—II of Fig. 1.

Fig. 3 is an enlarged plan view of the driving magnet holder.

Fig. 4 is a sectional view taken on line IV—IV of Fig. 3.

Fig. 5 is an enlarged side elevational view of one of the miniature vehicles.

Fig. 6 is an inverted plan view of the vehicle shown in Fig. 5.

Fig. 7 is a sectional view taken on line VII—VII of Fig. 6, with parts left in elevation.

Fig. 8 is a sectional view taken on line VIII—VIII of Fig. 6.

Fig. 9 is a sectional view taken on line IX—IX of Fig. 7.

2

Fig. 10 is an inverted plan view of the forward portion of a miniature vehicle, showing a modified form of front wheel mounting.

Fig. 11 is a sectional view taken on line XI—XI of Fig. 10.

Fig. 12 is a horizontal sectional view of the device taken just below the platform, showing another method of moving the driver magnets.

Fig. 13 is a sectional view taken on line XIII—XIII of Fig. 12, with parts left in elevation.

Fig. 14 is a fragmentary sectional view taken on line XIV—XIV of Fig. 12, with parts left in elevation.

Like reference numerals apply to similar parts throughout the several views, and the numeral 2 applies to a housing shown in Figs. 1 and 2, said housing comprising a rectangular box open at one side and having a back wall 4, end walls 6, and a bottom 8. The top of said box is closed by a horizontal platform 10 comprising a thin sheet of a suitable non-magnetic material such as aluminum, brass, wood, fibre, or plastic, said platform being fixed to back wall 4 and end walls

25 6 by suitable brackets 12. Said back and end walls, and an upwardly extending wall 14 disposed along the edge of platform 10 at the open side of housing 2, extend above platform 10 to form a rail for preventing the miniature vehicles 16 from running off the edge of said platform at any time. The open side of housing 2 provides an opening 18, as shown in Fig. 2, through which the operator may extend his hand and arm to manipulate the driving magnet holder 20, hereinafter described.

Each miniature vehicle 16, as best shown in Figs. 5 to 9, comprises a body 22, made of molded plastic or other light weight non-magnetic material and formed, in the particular representation shown, to simulate a racing car and driver, although it is apparent that other forms could be used, if desired. The front wheels 24 of the car are carried at the outer ends of a front axle

26, being carried for rotation by flanged bushings 28 pressed tightly onto the ends of said axle. Axle 26 is curved, so that the end portions are disposed rearwardly of the central portion, and wheels 24 are in axial alignment. A short rigid

30 shaft 30 is welded or otherwise fixed at its lower end to the midpoint of axle 26, and extends upwardly and slightly forwardly into a socket 31 provided therefor in solid portions 32 of the body 22, as best shown in Fig. 8. Shaft 30 rotates axially, and is prevented from falling free of the body when the car is lifted by a clip 34

fixed to the lower side of the body and extending in spaced relation beneath axle 26.

The rear wheels 36 of the car are carried rotatably in flanged bushings 28 pressed tightly on the end portions of rear axle 38. Said rear axle is straight, and the central portion thereof passes through a vertically enlarged slot 40 formed in a downward extension 42 of car body 22. Said axle is prevented from moving longitudinally in slot 40 by means of spacer sleeves 44 carried on the axle and disposed between extension 42 and bushings 28, as best shown in Fig. 9. Thus the rearward axle is free to tilt in a vertical plane relative to the car body.

A permanent bar magnet 46 is adapted to be inserted vertically into a socket 48 provided in a solid portion 50 of the car body.

As best shown in Fig. 8, said magnet is removably retained in said socket by a spring detent 52 carried by car body 22 and adapted to project resiliently into a groove 54 formed in one side of the magnet. This insures that the magnet can not be inserted with the wrong polarity. The magnets should be removed when shipping or storing to prevent the magnets from becoming neutralized by contact with other magnets. The lower end of magnet 46 is disposed in closely spaced apart relation to platform 10. It is desirable that the magnet be disposed rearwardly from the axis of front wheels 24, in order that the downward pull of the driving magnets urge all of the wheels against the platform, thus removing any tendency to rock the car forward on its front wheels. At the same time, the magnet should be close to the front wheels in order that the steering force be transmitted directly to the front wheels, thus minimizing any tendency for the rear wheels to skid transversely. It has been found that placing the magnet substantially in line with the rearmost edges of front wheels 24 produces the greatest stability and steerability.

Driving magnet holder 20, best shown in Figs. 3 and 4, comprises a circular turntable 56 made of plastic or other non-magnetic material, and having a plurality of permanent bar magnets 58 molded or otherwise securely fixed in said turntable at equally spaced points about the periphery thereof. Two magnets are shown, though a greater number could be used if desired. Said turntable is carried for free axial rotation on pin 60, to the downwardly extended end of which is fixed a handle 62. By means of said handle, the operator is enabled to hold turntable 56 against the lower surface of platform 10, and to move it slidably thereagainst. It will be noted that driving magnets 58 are so disposed that the upper poles thereof cooperate with unlike poles of the car magnets 46, whereby each driving magnet is adapted to drive and steer one car.

The above described wheel mounting of the cars, and the relation of the magnets thereto, provides for easy, accurate steering of the cars. The castering of front wheels 24 provides that they will trail accurately. The tilting of shaft 80 provides that the car will bank realistically to the inside on curves. That is, the car body will tilt laterally while the wheels remain on the platform. The pivotal mounting of rear axles 38 permits the rearward end of the car to tilt also without lifting the outside rear wheel from the platform. The castering of the front wheels, in combination with the tilting of shaft 80, provides that the car body will be slightly elevated as well as tilted when making a turn. At the rear axle, the car body will be supported on one of sleeves 44 at point 64

when the car is in a right turn, as shown in Fig. 9, and on the other sleeve 44 at point 66 when the car is in a left turn. Thus when the car turns either direction, the car body is slightly elevated against the force of the magnetic attraction acting on magnet 46. Since the magnet urges the car body downwardly, the magnet itself has the effect of urging the car into a straight line of travel and of holding it there so long as driving magnet 58 travels in a straight line. This feature to a large degree eliminates shimmying of the front wheels. It will be noted that the distance between driving magnets 58 carried by turntable 56 is greater than the overall length of one car, in order that the two cars driven by said magnets may be turned freely in any direction without colliding or in any way interfering with each other.

Turntable 56 is provided with upwardly projecting lugs 68 equally spaced about the periphery thereof. These lugs maintain magnets 58 in spaced apart relation to the lower side of platform 10, and move slidably against said platform. This contact with the platform causes the turntable to rotate on pin 60. As the turntable rotates the cars will alternately take the lead, depending on the angular position of the turntable, and will pass each other, alternate in taking the inside and outside positions, and thus realistically imitate a race. The rotation of the turntable will not be uniform, but will be a matter of chance, depending on the pressure exerted by the operator, minute irregularities of the lower surface of the platform, etc. Thus there is no means for forecasting which car will be ahead at any given instant.

In the modified car 70 shown in Figs. 10 and 11, the structure is the same as that of car 16 except for the mounting of the front wheels 24. Each 40 of said wheels is carried rotatably in a flanged bushing 28 pressed on the outer ends of a short axle 72. The inner ends of said axles are each formed to present a loop 74. A connecting rod 76 is disposed horizontally and has its end portions carried respectively for pivotal and limited universal movement in said loops. A rod 78 is fixed to each axle 72 intermediate the ends thereof. Said rod extends horizontally forwardly, then horizontally inwardly, and has its inner end portion bent upwardly to form a shaft 80 carried for axial rotation in a forwardly and upwardly inclined socket 82 formed in a solid portion 84 of car body 22. A clip 86 secured to the car body extends beneath the lower ends of shaft 80 to prevent accidental removal of said shafts from their sockets. Shafts 80 are parallel and spaced apart transversely of the car body, but not so far apart as the pivotal connections of connecting rod 76.

60 The operation of the car shown in Figs. 10 and 11 is the same as the car in Figs. 5 to 9 except that the pivoting of the front wheels about separate, spaced apart shafts 80, and the relation of said shafts to the pivotal points of connecting rod 76, causes the front wheels to toe slightly inwardly whenever the car enters a turn. This has been found to reduce skidding and thus to provide better steerability of the car.

Figs. 12 to 14 show another method of supporting, moving, and providing chance rotation of driving magnet holder 20. The turntable 56 of said holder, carrying the driving magnets 58, is carried for free axial rotation on pin 88. The 70 downwardly extended end of said pin is rigidly fixed to a bracket 90, which is in turn fixed to a

flexible belt 92 by rivets 94, as best shown in Fig. 14. Said belt moves in a plane at all points uniformly spaced below platform 10, and passes about two horizontally disposed flanged pulleys 96 and 98, each of said pulleys being fixed to a shaft 100 journaled respectively at its upper and lower ends in bearing 102 fixed to platform 10 and bearing 104 fixed to housing bottom 8. A bevel gear 106 carried on shaft 100 below pulley 98 meshes with a bevel gear 108 mounted on shaft 110 and is driven by motor 112 through a suitable speed reduction unit 114. Said motor and speed reducing unit are mounted on the housing bottom 8. The reaches of flexible belt 92 extending between pulleys 96 and 98 are carried slidably in channel guide members 116 welded or otherwise rigidly secured to support standards 118 mounted on the housing bottom 8. Bracket 90 carrying magnet holder 20 extends through the open outer side of said channel guide members. Pulleys 96 and 98 and guide members 116 serve to support belt 92 in such a manner that magnet holder 20 at all times moves in slightly spaced apart relation from the lower side of platform 10. It does not contact said platform.

A rail 120 of any suitable non-magnetic material is fixed to the lower surface of platform 10. Said rail is of substantially oval shape, and is so disposed as to be spaced slightly outwardly from the outer edge of the orbital path of driving magnet holder 20. A plurality of permanent bar magnets 122 are fixed to the lower edge of said rail in spaced relation therearound. Said magnets are substantially radially related to the path of magnet holder 20, the inner poles thereof being adapted to cooperate with the lower poles of driving magnets 58, as shown in Fig. 14. Thus if either of magnets 58 passes closely enough to any of magnets 122 as magnet holder 20 moves along beside rail 120, the force of attraction between said magnets will cause turntable 56 of the holder to rotate on pin 88, which in turn causes cars 16 on platform 10 to change their relative positions. The inertia of the turntable, and of the moving cars above the platform, will tend to keep the turntable rotating. If, on the other hand, neither of magnets 58 pass magnets 122 closely enough to be affected thereby, turntable 56 will not be affected by magnets 122. The outcome of a race between cars 16 is therefore purely a matter of chance.

The number and spacing of magnets 122 could be varied at will, and also the polarity of said magnets. Likewise, the number of magnets 58 carried by turntable 56, and the number of cars 16 driven thereby, could be altered. Also, though the vehicles 16 are shown as having the form of racing cars, it is apparent that they could be formed to represent many other objects such as animals or human beings, as long as they are supported by the wheel arrangement shown. These and many other minor variations of construction and operation could be made without departing from the spirit of the invention.

What I claim is:

1. A magnetic toy comprising a platform, a vehicle body, front and rear axles carried movably by said vehicle body, a wheel mounted rotatably at each end of both of said axles for supporting said vehicle body on said platform, a first magnet carried by said vehicle body intermediate said front and rear axles, and a second magnet carried movably beneath said platform and adapted to cooperate with said first magnet

to propel said vehicle, said front axle being pivotally castered to said body on an upwardly and forwardly inclined axis, whereby whenever said front axle is turned said vehicle body will be tilted inwardly on said axles relative to said turn.

2. A magnetic toy comprising a platform, a vehicle body, a shaft carried by said vehicle body for axial rotation about a forwardly and upwardly inclined axis, a horizontal front axle fixed at its midpoint to said shaft and having its end portions offset rearwardly, a rear axle carried by said vehicle body for pivotal movement in a vertical plane transverse to said vehicle body, a wheel mounted rotatably at each end of both of said axles for supporting said vehicle on said platform, a first magnet mounted in said vehicle body intermediate said front and rear axles, a second magnet carried beneath said platform and adapted to attract said first magnet through said platform, and means for moving said second magnet to propel said vehicle over said platform.

3. A magnetic toy comprising a platform, a vehicle body, a shaft carried by said vehicle body for axial rotation about a forwardly and upwardly inclined axis, a horizontal front axle fixed at its midpoint to said shaft and having its end portions offset rearwardly, a rear axle carried by said vehicle body for vertical movement, said vehicle body being supported by said rear axle at two transversely spaced points whereby when said body is tilted it will be elevated from said axle, a wheel mounted rotatably at the ends of both of said axles for supporting said vehicle movably on said platform, a first magnet carried by said vehicle body substantially in line with the rearward edge of the front wheels and having one of its poles closely adjacent said platform, a second magnet carried beneath said platform and having its opposite pole closely adjacent the lower surface of said platform and adapted to attract said first magnet through said platform, and means for moving said second magnet whereby said vehicle is propelled over said platform.

4. A magnetic toy comprising a non-magnetic platform, a plurality of steerable vehicles supported by said platform, a magnet carried by each of said vehicles and having one pole thereof closely adjacent said platform, a turntable disposed beneath said platform, a support for carrying said turntable for rotation about a vertical axis, a plurality of magnets carried by said turntable, each of said magnets having one pole disposed closely adjacent said platform and corresponding with one of the magnets carried by said vehicles, and means for moving said turntable support in parallel relation to said platform.

5. A magnetic toy comprising a non-magnetic platform, a plurality of steerable vehicles supported by said platform, a magnet carried by each of said vehicles and having one pole thereof closely adjacent said platform, a turntable disposed beneath said platform, a plurality of magnets carried by said turntable, said turntable magnets being respectively spaced apart a greater distance than the length of one of said vehicles and adapted respectively to cooperate with one of the magnets carried by said vehicles, and a handle fixed to said turntable for rotation about an axis at right angles to said platform, whereby said turntable may be moved in sliding contact with the lower surface of said platform.

6. A magnetic toy comprising a non-magnetic platform, a plurality of steerable vehicles supported by said platform, a magnet carried by

each of said vehicles and having one pole thereof closely adjacent said platform, a turntable disposed beneath said platform, a plurality of magnets carried by said turntable, said turntable magnets being respectively spaced apart a greater distance than the length of one of said vehicles and adapted respectively to cooperate with one of the magnets carried by said vehicles, an endless belt carried for movement in a plane parallel to and beneath said platform, means for driving said belt, and means for mounting said turntable on said belt for axial rotation, whereby said turntable is maintained in closely spaced relation from said platform.

7. A magnetic toy comprising a non-magnetic platform, a plurality of steerable vehicles supported by said platform, a magnet carried by each of said vehicles and having one pole thereof closely adjacent said platform, a turntable disposed beneath said platform, a plurality of magnets carried by said turntable, said turntable magnets being respectively spaced apart a greater distance than the length of one of said vehicles and adapted to cooperate respectively with one of the magnets carried by said vehicles, an endless belt carried for movement in a plane parallel to and beneath said platform, means for driving said belt, means for mounting said turntable on said belt for axial rotation, whereby said turntable is maintained in closely spaced relation from said platform, and means for rotating said turntable on its axis.

8. A magnetic toy comprising a non-magnetic platform, a plurality of steerable vehicles supported on said platform, a magnet carried removably by each of said vehicles and having one pole disposed closely adjacent the surface of said platform, an endless belt adapted to move in a plane uniformly spaced beneath said platform, means for driving said belt, a turntable mounted for axial rotation on said movable belt and adapted to move in closely spaced apart relation to the lower surface of said platform, a plurality of magnets carried by said turntable in spaced relation about the periphery thereof, each of said magnets being vertically disposed with its upper pole adjacent said platform and

adapted to attract one of the magnets carried by said vehicles, and a plurality of magnets carried by said platform and disposed in spaced relation to an edge of the orbital path of said turntable, whereby to cause axial turning of said turntable as it moves about its orbital path.

9. A magnetic toy comprising a non-magnetic platform, a plurality of steerable vehicles supported on said platform, a magnet carried removably by each of said vehicles and having one pole disposed closely adjacent the surface of said platform, an endless belt adapted to move in a plane uniformly spaced beneath said platform, means for driving said belt, a turntable mounted for axial rotation on said movable belt and adapted to move in closely spaced apart relation to the lower surface of said platform, a plurality of magnets carried by said turntable in spaced relation about the periphery thereof, each of said magnets being vertically disposed with its upper pole adjacent said platform and adapted to attract one of the magnets carried by said vehicles, and a plurality of magnets carried by said platform in spaced relation therebelow and disposed in spaced relation to the outer edge of the orbital path of said turntable, said last named magnets being adapted to cooperate with the lower poles of said turntable magnets to cause chance axial rotation of said turntable as it moves around its orbital path.
